ATTORNEY

UNITED STATES PATENT OFFICE

FRED L. WAGAR, OF WAGAR, ALABAMA

EXHAUST VENTILATOR

Application filed December 28, 1928. Serial No. 329,069.

The object of my invention is the provision of means for drawing air, smoke and the gases attending combustion from a chimney, and also air from various structures where ventilation is desirable, the main motive force for creating an upward draft being the energy of wind in motion impinging upon obliquely disposed deflecting surfaces.

10 The invention consists in certain novelties of construction and in the combinations of parts as herein set forth and claimed.

15 The accompanying drawings illustrate an example of the embodiment of the invention, the parts being constructed and combined according to the best mode of procedure I have so far devised for the purpose.

20 Figure 1 is a part plan and part sectional view taken in a horizontal plane 1—1 of Figure 2.

25 Figure 2 is a part sectional and part elevation view of the whole device taken in approximately a vertical plane through the center of Figure 1.

30 Figure 3 is a top plan view of the rotary arrow-headed wind vane for deflecting air from the opening to the chimney.

35 The device deflects moving air, as wind, upwardly at A, downwardly at B and outwardly in opposite directions horizontally at C, C; that is, away from the chimney opening.

40 The numeral 1, in this example, designates the chimney; 2, the frustum of a cone having a circular flange 3 adapted to be secured to the top of the chimney in any suitable way; 4, the top horizontal plate with an opening 5 corresponding to the diameter of the chimney opening; 6, a central vertical pipe secured to the deflector and extending downwardly into the chimney opening, where it is secured in position in any suitable way; and 7 is a conical air deflector spaced parallel with and from the top surface of the frusto-conical deflector and the opening covered by a horizontal plate 8, as shown.

45 A vertical rod 9 is disposed axially of the chimney opening, the frusto-conical deflector and the conical deflector. The rod

may be threaded at points 10, 11, 12, 13 to receive threaded nuts 14 which clamp the rod to the crossbars 15, 16, 17 and the plate 8.

55 Between plates 4 and 8 is pivoted the arrow-headed wind vane air deflector. The arrow head is formed of metal and the sides 18, 19 are obliquely disposed to each other. Cross plates 20, 20 and obliquely disposed plates 21, 22 preferably close the space between the plates 18, 19. The shaft 23 of the wind vane is secured at one end to the arrow head and the opposite end 24 widened to provide a relatively large area for the wind impinging upon it.

60 The shaft 23 has a bearing 25 with a wearing thimble 26, said thimble engaging the bearing 27 fixed upon the central rod. Ball bearings for the shaft of the vane may 65 be used if desired.

70 Obviously, a current of air in motion, as wind, will be deflected downwardly by the frusto-conical deflector, upwardly by the conical deflector, and outwardly in a horizontal plane by the arrow-headed vane, and away from the chimney opening, thus creating a vacuum space at the chimney opening so that air, smoke and the gases attending combustion will flow out of the chimney.

75 As the arrow-headed vane can rotate relatively to the fixed rod, the point of the arrow head will always point to the air in motion. The device is adapted for use not only in connection with a chimney but in connection with a pipe or flue for exhausting or drawing air from a room or other structure.

80 While I have illustrated and described only one example of the embodiment of the invention, it may be embodied with numerous changes in the details of construction, and the dimensions adapted to the pipe or chimney in connection with which the device is to be used.

85 What I claim is:

90 1. The combination in an air exhausting device, of a fixed frusto-conical air deflector having a horizontally disposed cover plate 4 with a central opening, a fixed conical air deflector with a horizontal plate 8, a rotary

arrow headed vane air deflector located between the two said plates 4 and 8, said arrow headed vane air deflector comprising an arrow head with its sides 18, 19 obliquely disposed to each other in vertical planes and a shaft extended horizontally beyond the plates 4 and 8, and fixed means with a bearing for the rotary arrow headed vane air deflector.

10 2. The subject-matter of claim 1 wherein the means constituting a bearing for the rotary vane air deflector consists of a fixed rod 9 which also supports the conical air deflector.

15 3. The combination in an air exhausting device, of a fixed frusto-conical air deflector having a horizontal plate 4 with a central opening, a crossbar at the opening, a fixed conical air deflector with a plate 8, a rod 9 secured to plate 8 and the said crossbar, and an arrow headed vane air deflector located between the two said plates 4 and 8 and mounted to rotate on the said rod.

20 4. The combination in an air exhaust device, of a rod, a bearing on the rod, means for fixedly supporting the rod at the opening of a chimney or outlet means for the products of combustion, a suitably supported horizontally disposed plate with a central opening surrounding the rod, a conical air deflector secured to the top end of the rod, and a rotary arrow headed vane air deflector comprising at one end an arrow head with sides vertically disposed and a shaft rotatably mounted on the bearing carried by the rod, said arrow head being located between the plate with the central opening and the conical air deflector, and the said shaft extending outwardly beyond the conical air deflector.

25 40 In testimony whereof I affix my signature.
FRED L. WAGAR.
